UNITED STATES PATENT OFFICE.

LAURENT BREVAL, OF PARIS, FRANCE.

IMPROVEMENT IN APPARATUS FOR EXPRESSING LIQUID FROM SPENT TAN-BARK.

Specification forming part of Letters Patent No. 135,317, dated January 28, 1873.

To all whom it may concern:

Be it known that I, LAURENT BREVAL, of Paris, France, have invented a new and useful Press for the Extraction of a Liquid from Spent Tan-Bark or other like matter; and do hereby declare the same to be fully described in the following specification and represented in the accompanying drawing, of which—

Figure 1 is a front elevation, and Fig. 2 a vertical section of such press. Fig. 3 is a section, on an enlarged scale, of the delivery-roller, the straining-bar, and the compressing-rollers, to be hereinafter described. Fig. 4 is a top view of the delivery-roller, the straining-bar, and the lower or smooth compressing-roller.

By means of the said press spent tan-bark or wet sawdust may be deprived of liquid, so as to be capable of being used as fuel. The press may also be used for the extraction of juice from sugar-cane or various other vegetable matters.

The nature of my invention consists in the arrangement and combination, substantially as hereinafter described, of a fluted delivery-roller, a perforated or foraminous curved straining-bar, and two compressive cylinders, one being fluted and the other plain on its cylindrical surface or periphery; such devices being provided with a hopper and inclined plane and certain other adjuncts, all substantially as hereinafter explained, and as represented in the accompanying drawing.

Such drawing exhibits the press as having the channeled cylinder or pressure-roller C arranged directly over the smooth-faced pressure-roller B; also, as having the fluted delivery or feed roller A arranged in rear of the bite of the said two pressure-rollers. The perforated bar D is disposed concentrically with the upper pressure-roller C, or thereabout, and between the delivery-roller A and the lower pressure-roller B, all being as shown. A hopper, T, formed and arranged with the delivery and pressure rollers, in manner as represented, serves to receive the wet spent tan-bark and convey it to the bite of the rollers A C. The channels of the delivery-roller I prefer to make helicoidal or to arrange in long helices, as shown in Fig. 4. The bar D is pierced with numerous fine and conical holes, each having its larger diameter at bottom of the hole in

order that the hole, while the machine may be in operation, may not become clogged with bark. The said bar D, at its ends, should be suitably supported, and be provided with adjustments to enable it to be readily fitted closely to the periphery of the delivery or feed roller A. The cylinder B has flanges b b at its ends to admit or regulate the width of the sheet of pressed material discharged from it. Furthermore, the cylinder C has its journals supported in boxes arranged to slide vertically in guides within the frame H, by which the main operative parts are supported. Levers M M, by means of rods C³, serve to press downward the said boxes, such levers, by rods r, being connected with other levers, S, arranged as shown, and having weights T' suspended from them by rods R R. Underneath the rollers B C is a receiving trough or pan, G, provided with an educt, g, to lead into a drain or conduit, or other proper receptacle, arranged below such educt. For imparting motion to the cylinder C there is fixed upon its shaft a spur-gear, C¹, which engages with a pinion, C², fixed upon a horizontal shaft, d. The said pinion engages with a like gear, b', fixed on a shaft, e. A similar gear fixed on the shaft e engages with a spur-gear, B², fixed upon the shaft of the roller B. Furthermore, on the shaft e is a gear, f, which engages with a pinion, g', fixed on a driving-shaft, h, arranged as represented, and provided with a fly-wheel, V, and fast and loose pulleys P P'. An inclined plane, J, fitted to the frame H, and nearly resting on the roller B, is arranged as shown, the purpose of it being to discharge from the machine the pressed material or tan-bark.

In using the said machine, while its pressure-cylinders may be in revolution the material to be pressed is to be thrown into the hopper, from whence it will be delivered between the two rollers A and C, and there receive its first pressure, the liquid extracted flowing upon the foraminous or perforated bar D, over and against whose surface the material will be forced by the roller C. Finally, the material will pass between the rollers B and C, and by them be still further compressed, the liquid expressed being received upon the perforated bar, and caused to run through such into the receiver G. Gears x y, fixed on the shafts of

the rollers A C, impart motion to the feed-
roller A.

What I claim as my invention, in the ma-
chine as described, is—

The combination of the rollers or cylinders
A B C and the perforated bar D, arranged as
set forth, the rollers B C being provided with
mechanism for revolving them, as specified,
and the upper of said rollers B C being mov-
able vertically and furnished with pressure
devices, essentially as described, and the sys-
tem of rollers A B C and perforated bar D

being provided with a hopper, T, a liquid-re-
ceiver, G, and an inclined discharger or plane,
J, or one or more of such, as occasion may
require, the whole being substantially as and
for the purpose as explained.

In witness whereof I, the said LAURENT
BEEVAL, have hereto set my signature this
7th day of October, 1872.

L. BREVAL.
